UNITED STATES PATENT OFFICE.

FRED DODGE, OF CRICHTON, LOUISIANA, ASSIGNOR OF ONE-HALF TO FRED A. GRIFFIN,
OF CRICHTON, LOUISIANA.

ELEVATOR APPLIANCE.

1,219,268.

Specification of Letters Patent. Patented Mar. 13, 1917.

Application filed June 3, 1916. Serial No. 101,593.

To all whom it may concern:

Be it known that I, FRED DODGE, a citizen of the United States, residing at Crichton, in the parish of Red River and State 5 of Louisiana, have invented certain new and useful Improvements in Elevator Appliances; and I do hereby declare the following to be a full, clear, and exact description of the invention, such as will enable others 10 skilled in the art to which it appertains to make and use the same.

The present invention relates to improvements in elevator appliances for use more particularly in raising and lowering sucker rods out of and into wells; and it consists 15 in constructions, combinations and arrangements herein described and claimed.

In the accompanying drawings forming a part of this application, and in which 20 similar reference symbols indicate corresponding parts in the several views:

Figure 1 is a front elevational view of an elevator appliance as constructed in accordance with the present invention.

25 Fig. 2 is a similar view shown partly in section.

Fig. 3 is an end elevational view of the improved appliance shown partly in section.

30 Fig. 4 is an enlarged view of the head; and

Fig. 5 is a cross sectional view taken on the line 5—5 in Fig. 2.

Referring more particularly to the drawings, 1 designates a bail which is adapted 35 to be secured to a hook indicated at 2; such hook being supported from the elevator cable.

At 3 is shown a yoke which may be solid 40 or formed in the two pieces shown in the drawings, such pieces including arms 4 and 5 connected together by bolts or other means 6. The yoke is formed with a shank 7 shouldered as shown at 8 in Fig. 2 and reduced thereabove at 9, where it swivelly 45 engages through an opening in the bail 1. The end of the reduced portion 9 is threaded to receive a pair of lock nuts 10 and 11, the upper nut 10 of which is preferably secured 50 to the portion 9 by a key 12, or other suitable means. A washer 13 is interposed between the lower nut 11 and the bail 1.

The lower ends of the arms 4 and 5 are 55 formed to provide openings or bearings 14 and 15 in which are journaled the trunnions

16 and 17 of a head 18. The head may be made either solid or in sections, and is provided with a slot 19 into which is arranged to be received the squared portion of a sucker rod. The sucker rod is confined in 60 the recess 19 by a latch or trigger 20 pivoted as at 21 in a recess 22, which may open through the edge of the head 18, as shown to advantage in Fig. 4 to permit the insertion and removal of the trigger 20 without 65 the necessity of separating the head section. A notch 23 may or may not be provided in the wall of the slot 19 opposite the recess 22 to receive the end of the trigger 20 and 70 form an abutment for the same.

The trigger is to be actuated from a rod 24 fitted to reciprocate in a groove 25 in the head 18, and connected to the trigger 20 by wire or other link 26. The rod 24 projects beyond the head 18, where it is 75 threaded to receive a cap nut 27 between which and a shoulder 28 formed in the groove 25 is confined a coil spring 29. The coil spring 29 normally acts to project the rod 24 outwardly, thus pulling upon the 80 link 26 and swinging the trigger 20 to the position shown in Figs. 1 and 4, where it extends across the slot 19, confining the sucker rod in place therein. When, however, it is desired to release the sucker rod 85 the cap nut 27 is depressed in opposition to the coil spring 29, which action moves the rod 24 and link 26 downwardly to the dotted line position shown in Figs. 2 and 4, where the trigger 20 will be withdrawn 90 from the slot 19 and into the recess 22, thus leaving the sucker rod free to escape therefrom.

The sucker rod may be placed in the slot 19 after swinging the head 18 to horizontal 95 position by forcing the squared portion of such sucker rod inwardly against the inclined edge of the trigger 20, such trigger yielding automatically and swinging within the recess 22 to permit the entrance of 100 the sucker rod. After the sucker rod has passed the trigger 20, coil spring 29 will automatically return the same to locking position, and the elevator is thereupon put in 105 operation to hoist the rod from the well.

After the sucker rod has been hoisted to the capacity of the elevator, the yoke 3 may be rotated in the bail 1 to act as a wrench, unscrewing the joint between the adjacent 110 sections of the sucker rod at the mouth of

the well, after which the detached sections of the sucker rod are removed from the head 18 by tripping the trigger 20, as above described. The elevator is then operated to 5 lower the appliance, whereupon the slot 19 in the head 18 is engaged with the uppermost of the remaining sections of the sucker rod, and such sections are subsequently hoisted and detached until the whole of the 10 rod is removed from the well.

For the purpose of steadyng the head 18 in the yoke 4, it is advantageous to employ some such device as shown in the drawing, and which preferably consists of casings 30 15 threaded into the head 18 and being provided with perforated flanges 31 through which slidably project plungers 32. The plungers have shoulders 33 for preventing the withdrawal thereof from the casings 30, and such shoulders engage one end each of coil springs 34 fitted in said casings 30, which have a tendency to yieldingly project the plungers 32. The plungers 32 are adapted to fit sockets 35 in the arms 4 and 20 5, as shown in Figs. 1 and 2, where they will securely hold the head in the position shown, but which may be disengaged by applying force to move the head out of the vertical position.

It is obvious that those skilled in the art 30 may vary the details of construction and arrangements of parts without departing from the spirit of my invention, and therefore I do not wish to be limited to such features except as may be required by the claim. 35

I claim:

In an appliance of the character described, the combination of a bail, a yoke swivelly supported in said bail and having bearings and sockets adjacent said bearings, 40 a head comprising disk sections secured together, trunnions on said disk sections journaled in the bearings in said yoke, said head having a slot therein, a recess to one side of said slot and a notch in the opposite 45 wall of said slot, a trigger pivotally mounted in said recess and adapted to swing across said slot with one end occupying said notch, a spring-pressed rod arranged in operative relation to said trigger, casings fitted in 50 said head, plungers in said casing adapted to enter the sockets in said yoke, and spring means for yieldingly projecting said plungers, substantially as described.

In testimony whereof, I affix my signature.

FRED DODGE.
